UNITED STATES PATENT OFFICE.

JOHN A. GURLEY, OF MINNEAPOLIS, MINNESOTA.

DESIGN FOR A CANDY.

Application filed February 27, 1925. Serial No. 12,502. Term of patent 3½ years.

To all whom it may concern:

Be it known that I, JOHN A. GURLEY, a citizen of the United States, residing at Minneapolis, in the county of Hennepin and State of Minnesota, have invented a new, original, and ornamental Design for Candy, of which the following is a specification, reference being had to the accompanying drawing, forming part thereof.

Figures 1 and 2 are opposite face views of a piece of candy mounted on a stick, showing my new design.

I claim:

The ornamental design for a candy, as shown.

JOHN A. GURLEY.
